BOILER

George Wilfrid Trotter, West Hartlepool, England

Application March 17, 1934, Serial No. 716,150
In Great Britain March 25, 1933

2 Claims. (Cl. 122—334)

I have filed an application in Great Britain No. 9104/33 filed the 25th day of March 1933.

The present invention relates to boilers, and particularly to water-heating boilers suitable for domestic uses such as the heating of buildings and greenhouses.

Objects of my invention are the utilization of the heating fuel to the highest degree, the maintenance of combustion of the fuel at all times so long as an adequate supply of fuel is furnished to the fire box or combustion chamber, the need for the minimum attention to the boiler to keep it in operation, and the attainment of these objects by a structure of simple form and compactness and one which will enable ash and clinker to be easily removed.

My invention consists in whatever is described by or is included within the terms or scope of the appended claims.

Fig. 1 is a longitudinal section through a boiler constructed in accordance with the invention.

Fig. 2 is a part sectional front view of Fig. 1.

Referring to the drawing, one form of boiler made in accordance with the present invention comprises a firebox-casing 1 having a forwardly inclined front wall and provided with horizontal and inclined firebars forming grates 2, 3, which are hereinafter called the bottom and the front grate respectively. The casing 1 is provided in its rear part with a water heating unit comprising upper and lower transverse tubes or water drums 4, 5, the upper drums 4 being arranged in a horizontal line, with the last one in proximity to the lower end of the flue 6, and the lower drums 5 being arranged in an inclined line with the first one adjacent to the rear edge of the bottom grate 2. The two sets of drums 4, 5, are each interconnected by five spaced water tubes 7 and also by two water jackets 8, one of which is arranged at one end of the two sets of water drums and the other at the opposite end thereof, and which constitute the side walls of the casing 1. In addition, as shown, said water jackets 8 extend across the front of the boiler.

As has been indicated, the horizontal tubes or drums 4 and 5 at opposite ends communicate with the headers or water jackets 8 that are in the opposite side walls of the boiler and the tubes 7 which are preferably oval in cross-section communicate at their ends with the tubes or drums 4 and 5.

Each of the lower drums 5 is arranged in a plane to the rear of the upper one 4 to which it is joined, so that the water tubes 7 are forwardly inclined from their lower ends, and con-

sequently the front set form an apertured wall parallel with the front wall of the firebox-casing, thus affording in conjunction therewith a forwardly inclined firebox or combustion space 9. The inclination of this last is such that fuel entering the feeding aperture of the boiler will fall on to the inclined front wall and be conducted therefrom on to the bottom grate 3.

In consequence of the inclination of the firebox or combustion space and the substantial difference in the levels of the upper portions of the spaces between the tubes 7 and the grate bars 3, a radiant surface is continuously maintained against the water tubes, so long as the firebox remains full of fuel, and for the following reasons:—Assuming that the hopper 10 and combustion space 9 are filled with fuel and that combustion is proceeding at full draught then the actual fire zone will slope from the bars 3 to the upper drum 4, making an acute angle with the front wall approximately as indicated by the dotted line in Fig. 1. Now as the fuel is consumed the natural tendency of the fire is to collapse vertically downwards and to fall away from the tubes 7. There is thus a tendency for a wedge-shaped space to form next to the tubes, but as fast as this forms it is filled in by the natural rolling action of the fire surface and the fall of fresh fuel from the reserve above. It will be seen such fresh fuel will always be supplied with hot air that has passed through the fire zone. Consequently, it will be immediately ignited so that a radiant surface is continuously maintained in contact with the tubes 7.

If the fire is allowed to burn out, the wedge-space next to the tubes will cease to be filled completely as the reserve of fuel above becomes smaller; the surface of the fire zone, however, will remain at substantially the same angle and the cold air will thus always have to pass through the fire zone.

A very important feature of my invention lies in the fact that before the air supply can reach the fresh fuel, such air must pass through the fire zone. If the fresh fuel should be supplied with cold air, the fire would very soon go out. With the boiler constructed in accordance with my invention, the combustion chamber or fire box can be filled completely with fuel with the assurance that it will continue to burn until all, or very nearly all the fuel is consumed. This result is due to the fact, in connection with the sloping or forwardly inclined rear face of the fire box, that the uppermost portion of the passages through the rear side of the fire box

are substantially higher than the air inlet through the grate 3 at the bottom of front wall of the fire box. With this arrangement the line of draught is upwardly inclined at an acute angle to the front wall and consequently, the upper surface of the fire zone is correspondingly inclined. If the air inlets in the front wall were as high as the apertures in the rear wall, the line of draught would run horizontally across the combustion chamber and the fuel would tend to fall vertically so that as soon as the fire settled a layer of fresh fuel would be formed within the line of draught and this fuel would not ignite owing to the fact that the air supply would be cold. With this arrangement, the fire would very quickly go out.

The lower edge of the front grate 3 is supported only at the ends so that a space is provided between it and the bottom grate 2 so as to allow of the ash and clinker being removed. The flue 6 in this particular case is arranged at the rear of the stove and a damper (not shown) is slidably arranged in the flue to control the draught passing therethrough. A front closure member would also be provided in front of the bars 3 so as to control the air inlet.

A hopper 10 is positioned at the front of the boiler and directly over the inclined fire zone 9. Said hopper 10 may be detachably mounted as shown. For this purpose its lower end is open and is made to fit in the usual feeding aperture, whilst a short distance from the lower end it is provided with an outstanding flange 11 so that when fitted into the feeding aperture the whole hopper will be firmly supported. The upper end of the hopper, on the other hand, is stepped outwardly so as to correspond with the diameter of the feeding aperture, and when the hopper 10 is in position the lid 12 normally used for the feeding aperture is placed in the top of the hopper, the same lid thus serving in both cases. It will thus be appreciated that the combustion of the fuel takes place within the space formed between the two water jackets, so that as much of the available heat as possible is utilized to heat the water contained within the unit, and further that by reason of the inclination of the combustion space the fuel carried in the hopper automatically replaces that consumed on the front grate, the fuel falling onto the grate by the action of gravity.

If desired one or more further hoppers may be mounted in the recessed upper portion of the one already in position.

55 The side and rear walls of the firebox are ex-

tended beyond the bottom grate, so that the lower edges of said walls may serve as feet for the boiler and form an ashpit. If desired, means such as an inclined baffle plate may be provided to assist in controlling the flow of fuel from the 5 hopper to the front grate as aforesaid.

I claim:—

1. A boiler for coke and like fuels of small volatile content, having a fire box or combustion space with a fuel inlet to its upper end, said fire 10 box or combustion space having forwardly inclined rear and front walls of rectilinear form in side elevation whereby the fire box becomes forwardly inclined as a whole, the rear wall being contiguous to said inlet and afforded by inclined water tubes spaced apart to form apertures for the passage of the hot gases from the fire box to the uptake and constituting the main surface to be heated, and the front wall being provided at the bottom with an air admitting 20 opening of such size and extent that the line of draught through the fire box is upwardly inclined at an acute angle to the front wall and in a direction approaching the vertical, the angle between the front wall and the bottom grate being approximately vertically below the topmost outlet aperture in the rear wall, the whole being so arranged that fuel is maintained in contact with the entire rear wall so long as the supply of fuel is maintained. 25

2. A boiler for coke and like fuels of small volatile content, having a fire box or combustion space with a hopper and fuel inlet to its upper end arranged to permit the unimpeded vertical entry of fuel over the full area of said upper end, 30 said fire box or combustion space having forwardly inclined rear and front walls of rectilinear form in side elevation whereby the fire box becomes forwardly inclined as a whole, the rear wall being afforded by inclined water tubes 35 spaced apart to form apertures for the passage of the hot gases from the fire box to the uptake and constituting the main surface to be heated, and the front wall being provided at the bottom with an air admitting opening of such size and 40 extent that the line of draught through the fire box is upwardly inclined at an acute angle to the front wall and in a direction approaching the vertical, the angle between the front wall and bottom grate being approximately vertically below the topmost outlet aperture in the rear wall, 45 the whole being so arranged that fuel is maintained in contact with the entire rear wall so long as the supply of fuel is maintained. 50
